UNITED STATES PATENT OFFICE.

LINUS YALE, JR., OF PHILADELPHIA, PENNSYLVANIA.

LOCK.

Specification forming part of Letters Patent No. 22,048, dated November 9, 1858; Reissued November 5, 1872, No. 5,131.

To all whom it may concern:

Be it known that I, LINUS YALE, Jr., of Philadelphia, in the State of Pennsylvania, have invented a new and Improved Manner of 5 Constructing Locks for Safes, Banks, Doors, &c.; and I do hereby declare that the following is a full and exact description of the same, reference being had to the drawings hereunto annexed.

10 The nature of my improvement consists in providing a main bolt or bolts with two or more sets of stops or tumblers so arranged that by application of the proper key to or otherwise adjusting one set shall release the bolt irrespective and independent 15 of either of the other sets. These sets of tumblers may be of similar construction requiring the application of one common key or of entirely different kinds requiring a 20 different key or adjustment, the object being to provide a way to get into a safe at any time without violence, even though one part of the lock may be deranged by accident or otherwise.

25 In the drawings Figure 1, is a plan of the lock showing the general arrangement of two of the simplest form of tumblers to hold out the main bolt D, by the two fence pins B¹, and B², on the cross bolt C. Fig. 2, is a 30 vertical section of the same through 1, 1. Fig. 3, is a vertical section through 2, 2. Fig. 4, is a horizontal section through 3, 3. Fig. 5, is a plan of cross bolt C. Fig. 6, is another plan of cross bolt C moved into an 35 unlocked position. Fig. 7 is the key in section, E.

The main bolt D, slides in the usual manner by means of the key working in the one or the other of the two talons d¹ and d² in 40 the ordinary manner. The cross bolt C, is also provided with two similar talons c¹ and c² for another portion of the revolution of the key to engage in, and it also has two fence pins B¹ and B² fitted to pass through 45 the gatings a¹ and a² of the tumblers A¹ and A², respectively. These fence pins when the lock is locked stand immediately behind the arms or projections d³ and d⁴ on the main bolt D, thereby preventing its retraction 50 until provision is made for it by adjustment of one of the tumblers, hereinafter more particularly described. The cross bolt C is moved from its present position either one

way or the other as the key is applied above or below, the effect being precisely the same 55 on the bolt, whether the fence goes up or down as it releases it either way. The tumblers A¹ and A² slide in the same direction as the bolt D, being driven one way by the key, and back again by springs o¹ and o², 60 in the ordinary manner. They are gated a¹ and a² as usual for the passage of the fence pins B¹ and B². The drill pins F¹ and F² serve to steady the key in its revolution. 65

The drawing shows only the working parts of the lock without case or cover that all parts may be distinctly shown.

Operation:—By putting the key on to the drill pin F¹ and turning to the right the 70 wing or bit e will drive the tumbler A¹ to the proper distance to bring the gating a¹ opposite the fence pin B¹, when the key immediately engages in the talon c¹ and while still holding the tumbler in position, moves 75 the cross-bolt C until the fence pin B¹ has passed through the gating. Then by releasing the main bolt (for the other fence pin it will be observed does not require to pass through a gating in moving upward) when 80 the key having worked into the talon d¹ of the main bolt D retracts it at the same time it allows the tumbler to be driven back to its original position. But, should anything prevent thus adjusting the tumbler A¹ or 85 passing the fence pin B¹ through it and consequently the retraction by that means of the main bolt D, it will be seen that the key may be applied to the other drill pin F² and being revolved to the left will adjust 90 the tumbler A² to admit of its passing the fence pin B², thereby releasing the main bolt D precisely as well as though the other application had been successful, and entirely 95 regardless of the position of the tumbler A. In locking the key must of course be applied to the part unlocked as the one which is locked cannot be more locked.

I make no claim to the particular form of tumblers or other parts of this lock as my 100 improvement can be adapted and applied to any of the old forms of lock however simple or however complex and costly; but

I do claim—

Providing a main bolt or bolts with two 105 or more systems or sets of stops or tumblers

or their equivalents whether alike in form and construction or dissimilar—commanded by or obedient to one and the same key or its equivalent or by separate and distinct
5 keys or their equivalent—so placed and arranged, whether near or distant, that when its key is applied to either one set, that set

shall release the bolt irrespective and independent of either of the other sets substantially as and for the purpose described.

LINUS YALE, JR.
